United States Patent Office

Des. 231,683
Patented May 28, 1974

231,683

DISPLAY STAND FOR STRIP MATERIAL

James T. Rash, Las Vegas, Nev., and Gary Peacock,
Marion, Va., assignors to Mouldings, Inc., Marion, Va.

Filed Oct. 30, 1972, Ser. No. 301,759

Term of patent 14 years

Int. Cl. D6—04

U.S. Cl. D6—188

FIG. 4

FIG. 1 is a front perspective view of a display stand for strip material showing our new design;

FIG. 2 is a right side elevational view;

FIG. 3 is a rear elevational view; and

FIG. 4 is a top plan view.

We claim:

The ornamental design for display stand for strip material, as shown and described.

References Cited

UNITED STATES PATENTS

D. 118,458	1/1940	Smith	211—49 R X
D. 201,480	6/1965	Faber	D6—85
228,158	5/1880	Woods	D74—2 A
1,636,608	7/1927	Kenyon et al.	211—60 R

WINIFRED E. HERRMANN, Primary Examiner

J. CORRIGAN, Assistant Examiner